UNITED STATES PATENT OFFICE.

WILLIAM C. HOMAN, OF MERIDEN, CONNECTICUT, ASSIGNOR TO THE
EDWARD MILLER & COMPANY, OF SAME PLACE.

DESIGN FOR A CYCLOMETER-BODY.

SPECIFICATION forming part of Design No. 27,899, dated November 23, 1897.

Application filed September 8, 1897. Serial No. 650,993. Term of patent 3½ years.

To all whom it may concern:

Be it known that I, WILLIAM C. HOMAN, a citizen of the United States, residing at Meriden, county of New Haven, State of Connecticut, have invented a certain new and original Design for the Body of a Cyclometer, of which the following is a full, clear, and exact description.

My invention relates to a new and original design for a cyclometer-body.

Referring to the drawings, Figure 1 is a perspective view of the body of a cyclometer illustrative of my new and original design. Fig. 2 is an end elevation of the same.

The leading features of my design are the general outlines and ornamentation, as hereinafter set forth.

A is a casing of cylindrical outline, the edges of said casing A being provided with ornamental bands B of slightly greater diameter than the diameter of said cylinder. Projecting from the side of the casing A is an offset E, carrying a tubular body F of substantially cylindrical outline. The said body F is substantially parallel with the cylinder A and of considerably less diameter, as shown.

What I claim is—

The design for the body of a cyclometer, substantially as herein shown and described.

W. C. HOMAN.
